BRAUN OSCILLOGRAPH

Johannes Richter and Albert Knabner, Berlin, Germany, assignors to Telefunken Gesellschaft für Drahtlose Telegraphie m. b. H., Berlin, Germany, a corporation of Germany

Application May 16, 1930, Serial No. 452,880
In Germany May 17, 1929

3 Claims. (Cl. 250—27.5)

The Braun oscillograph is extensively used in the analyses of alternating currents. One of the recent developments in the construction of these tubes is that they have been equipped with heated 5 cathodes.

The present invention resides in various improvements of such a tube, and the advantages of the same concern both the manufacture and the technical end of the tube as well as the longer 10 life and greater sensitivity of the tube. According to the invention, the cathode, which may consist of a heated spiral positioned at right angles to the tube axis, is surrounded by a bowl or cup-shaped diaphragm. The latter, being 15 most suitably mounted together with the glass cup wherein the filament is contained, is provided with a separate lead-in so that a biasing potential may be applied thereto with a view to increasing the sensitiveness. By the particular 20 shape of the diaphragm, a separate cathode space is obtained inside the tube, while by the use of a biasing potential the emission of the cathode has to be lower, for a given thermionic current flowing through the anode channel. This in turn 25 means longer life of the tube.

The anode, which may consist, for example, of a slender metal tube, for example, a platinum tube, is sealed inside a glass bell, the end of which suitably is flush with the glass bell. The beaker-shaped diaphragm has a hole at its anterior end, the diameter thereof being somewhat larger than the diameter of the anode tube. The glass bell is fitted upon the diaphragm, and the anode can 30 be easily centered into the diaphragm opening. The diaphragm opening towards the inside of the beaker may be of a smaller diameter than in outward direction. During the evacuation process the diaphragm can be effectively out-gassed by applying positive potential thereto. It 35 is desirable to use an oxide cathode and also advisable to form the deflector plates and the electrode supports from a readily weldable non-magnetic metal, such as German silver. For the luminescent screen the use of fluorescent sub- 40 stances as extensively used for these purposes is 45 recommendable, though especially favorable is the admixture of halogens and their compounds, such as iodine, to the fluorescent material whereby firm sticking of the fluorescent substance to 50 the glass wall is insured. The anode protection resistance most suitably is sealed inside the vacuous vessel.

The accompanying drawing illustrates embodiments of the heated filament for a Braun tube 55 according to this invention.

By the accompanying drawing, Fig. 1 illustrates a sectional view through a completely assembled tube, and Figs. 2, 3 and 4 indicate the arrangement of the filamentary cathode within the tube, Figs. 2 and 3 showing the filamentary cathode transverse to the tube axis and Fig. 4 showing the filamentary cathode longitudinally of the tube axis. 5

Referring to the drawing, H is the heated filament spiral, B the cup-shaped or beaker-shaped 10 diaphragm surrounding the said spiral. The anode A is sealed in the glass bell G, and at its lower end it is located in front of the diaphragm opening D. F is the glass cup which serves for mounting the electrode assembly. As shown by 15 Fig. 1 a Braun tube T according to the invention, is provided with the usual fluorescent screen S, formed as above described and P and P' represent the deflecting plates, for obtaining horizontal and vertical deflections of the cathode ray 20 stream. These plates are preferably formed from non-magnetic material, such as German silver. The showing of the cup shaped member F and the manner of assembling the filamentary cathode H therein is shown in further detail by 25 Figs. 2 and 3 which represent on an enlarged scale the showing in Fig. 1. By Fig. 4 certain modifications and changes have been made to illustrate the formation of the filamentary cathode as extending longitudinally of the tube. 30

Having now described our invention, what we claim and desire to secure by Letters Patent is the following:

1. A cathode ray tube comprising a cathode member for emitting a cathode ray stream, a 35 non-metallic cup substantially surrounding the cathode and for supporting said cathode member, a diaphragm member carried by the non-metallic cup and extending outwardly from said cathode for limiting the path of the cathode rays emitted, 40 a fluorescent screen, and a tubular shaped anode member mounted within said diaphragm for projecting the cathode rays toward the fluorescent screen. 45

2. A cathode ray tube having a multi-turn 50 spiral oxide coated cathode member positioned transversely to the tube axis, an insulating member for supporting the cathode, a tubular anode member, a diaphragm supported from the cathode supporting member and having an opening concentric with the axis of the tubular anode, a supporting bell for positioning the tubular anode axially of the tube, a plurality of pairs of non-magnetic deflecting electrodes positioned substantially adjacent the anode for deflecting in 55

a plurality of directions at right angles to each other the cathode ray upon application of voltages thereto, and a fluorescent screen adapted to become luminous upon the bombardment of the generated cathode rays.

3. A cathode ray tube having a cathode member, a non-conducting member for supporting the cathode, a tubular anode member, a diaphragm supported from the cathode supporting member and having an opening concentric with the axis of the tubular anode, a supporting bell for posi-

tioning the tubular anode axially of the tube, at least one pair of non-magnetic deflecting electrodes positioned substantially adjacent the anode for deflecting the cathode ray developed within the tube upon the application of voltages to the said electrodes, and a fluorescent screen adapted to become luminous upon bombardment by the developed cathode ray. 5
